ARC TUBE SYSTEM

John W. Dawson, Auburndale, Mass., assignor to
 Raytheon Manufacturing Company, Newton,
 Mass., a corporation of Delaware

Application July 14, 1939, Serial No. 284,502

18 Claims. (Cl. 175—354)

This invention relates to an arc tube system, and more particularly to such a system in which two controlled arc tubes are connected inversely in order to supply a controlled alternating current load, such as a resistance welding load.

One of the principal objects of this invention is to devise a simple and reliable firing circuit for such arc tubes.

Particularly when using igniting electrodes of the type which are separated from a cool cathode by an insulating wall, it is desirable to impress substantially only positive impulses on the igniting electrode, as described and claimed in my co-pending application, Serial No. 254,203, filed February 2, 1939, for an improvement in Arc discharge starting arrangement and method.

Another object of this invention is to accomplish the above result in a simple and reliable manner.

In alternating current systems of this general nature, particularly in the case of resistance welding loads, it is desirable that if one of the arc tubes fails to conduct current upon the application of an igniting impulse to its igniting electrode, the other arc tube shall also be prevented from starting. If this is not done, the current supplied to the load has a substantially direct current component which is usually disadvantageous.

A further object of this invention is to devise means responsive to the absence of conduction in either tube for deenergizing the firing circuit of the other tube.

The foregoing and other objects of this invention will be best understood from the following description of an exemplification thereof, reference being had to the accompanying drawing wherein:

Fig. 1 is a diagrammatic representation of a circuit embodying the present invention; and

Figs. 2 and 3 are curves illustrating the operation of the system shown in Fig. 1.

The embodiment illustrated consists of two arc tubes 1 and 2 preferably of the mercury pool cathode type. These tubes contain mercury pool cathodes 3 and 4, and anodes 5 and 6, respectively, and are provided with igniting electrodes 7 and 8. Although these igniting electrodes may be of any type which initiate an arc on the mercury pool cathode by means of an igniting impulse supplied thereto, they preferably are of the type which consists of a conductor separated from the mercury pool by an insulating layer which preferably consists of glass. More particularly these igniting electrodes may be of the

form described and claimed in the copending application of Percy L. Spencer, Serial No. 259,355, filed March 2, 1939, for an improvement in Arc starting devices. In igniting electrodes of this kind, the glass layer on the igniting electrode conductor is in contact with the surface of the mercury pool, and the arc tends to form at some such point of contact. The upper ends of the electrodes 7 and 8 may be left exposed to the discharge so as to provide discharge paths 5 in parallel with the respective cathodes and igniting electrodes.

Two alternating current lines 9 and 10 are connected to supply a suitable alternating current load which may consist of a transformer 11 having a primary 12, a secondary 13, and a load 14. In the particular system shown, the load 14 may consist of a resistance welding load. The arc tubes 1 and 2 are interposed in one of the conductors 10 in order to control the flow of 10 current to the load. In order to permit alternating current to flow through the tube system, the two tubes are reversely connected by means of the crossed conductors 15 and 16. If the tubes 1 and 2 are conducting, current pulses of 20 one polarity will flow through tube 1, and current pulses of the opposite polarity will flow through tube 2, thus delivering alternating current to the load. If, however, tubes 1 and 2 are non-conducting, the load is deenergized.

30 Igniting transformers 17 and 18 are provided to supply igniting impulses to the igniting electrodes 7 and 8, respectively. These igniting transformers are provided with secondary windings 19 and 20. The secondary winding 19 is 35 connected between the igniting electrode 7 and the cathode pool 3, while the secondary winding 20 is connected between the igniting electrode 8 and the cathode pool 4. The transformers 17 and 18 are also provided with primary windings 40 21 and 22 which are supplied with igniting voltage impulses through a control circuit which is energized from a transformer 23 having a primary winding 24 connected directly across the tubes 1 and 2. For this purpose the two ends of the primary winding 24 are connected respectively to the two conductors 15 and 16. The transformer 23 also has a secondary winding 25 which is connected to the primary winding 21 45 through a rectifier 26, and to the primary winding 22 through a rectifier 27. The rectifiers 26 and 27 are preferably of the copper oxide type. A conductor 28 connects the point intermediate the rectifier 26 and the primary winding 21 to 50 55

the point intermediate the primary winding 22 and the rectifier 27.

Interposed in the connections leading from the secondary winding 25 is a pair of control contacts 29. These control contacts may be operated from a control pushbutton or from some suitable timing arrangement. Connected in series with the control contacts 29 in the connection leading from the secondary winding 25 is a pair of contacts which are normally closed by means of a contact arm 30. This contact arm 30 may be opened by a relay 31 having an actuating coil 32 connected from one side of the secondary winding 25 to the lower of the two contacts 29.

Connected directly across the tubes 1 and 2 is a series circuit consisting of a resistance 33 and a condenser 34. This circuit is to enable the incipient arc spots initiated by the igniting impulses supplied to the igniting electrodes 7 and 8 to progress rapidly into true arc spots irrespective of the nature of the main load. This feature is more fully described and claimed in the copending application of Wilcox P. Overbeck, Serial No. 271,679, filed May 4, 1939, for an improvement in Arc tube systems.

The operation of the system described above can be best understood by referring to the curves shown in Figs. 2 and 3. These curves do not purport to show quantitatively the current and voltages involved. However, they do represent in a general qualitative manner the operation of the system. In Fig. 2 the sine wave *a* represents the line voltage which appears across the conductors 9 and 10. The curve *b* represents the load current flowing to the primary winding 12. In the systems which are contemplated, particularly resistance welding systems, the current *b* lags the voltage *a*, and in the particular instance shown, this lag is about 60 degrees. As the current passes through zero, one of the arc tubes 1 or 2 goes out, and it is desirable that the other tube start immediately in order to deliver smooth alternating current to the load. The curve *c*, which represents the voltage across the tubes 1 and 2, shows that when one of the arc tubes goes out, the voltage across said tubes rises very rapidly to the instantaneous value of the line voltage at that particular moment. The system is so arranged that this voltage impulse is transmitted through the firing circuit so as to ignite the previously idle tube, which thereupon immediately starts conducting current so that the voltage across the tube then drops to the relatively low value of the arc tube drop. This operation takes such a short time that the rise in voltage across the tubes lasts for a very short time, and therefore these voltage impulses are represented in curve *c* by vertical lines. Of course it is to be understood that this change does occupy some time interval which, however, it is impractical to illustrate in Fig. 2. It will be seen, therefore, that the voltage across the tubes 1 and 2 supplies voltage impulses at exactly the right moment in order to alternately fire the tubes 1 and 2 so as to cause the alternating load current *b* to flow smoothly through said tubes. The primary winding 24 which is connected directly across the tubes 1 and 2 has this voltage wave *c* impressed upon it. This same voltage wave *c* is therefore impressed through the secondary winding 25 upon each of the primary windings 21 and 22 connected in series with their respective rectifiers 26 and 27. The rectifier 26 permits the voltage impulses of

one polarity to pass through the primary winding 21, while the rectifier 27 permits voltage impulses of the opposite polarity to pass through primary winding 22.

The manner in which the control circuit network affects the voltages supplied thereto will be described in connection with Fig. 3. The curve *d* represents the voltage appearing in one of the secondary windings of the igniting transformers, for example secondary winding 19, and therefore represents the igniting voltage impressed between the igniting voltage 7 and the mercury pool cathode 8. If we assume that the rectifier 26 passes those impulses of the curve *c* which extend above the zero axis, we see that the voltage *d* appearing in the secondary winding 19, which is also substantially the voltage across the primary winding 21, has substantially the same shape as the curve *c* for as long as said curve *c* extends above the zero axis. As the curve *c* tends to reverse, the rectifier 26 stops conducting current. However, at this time current is flowing through the primary winding 21, and if this current were suddenly stopped, a relatively large back voltage would be induced in the primary winding 21, and therefore in the secondary winding 19 which would supply a voltage impulse to the igniting electrode 7 in the opposite direction to that of the main igniting impulse. The polarities of the various windings are so chosen that this main igniting impulse represented by the vertical portions of curve *d* makes the igniting electrode 7 positive with respect to its associated pool cathode 8. If, however, voltage impulses of the opposite polarity were permitted to be supplied to the igniting electrode 7, the disadvantages described in my copending application referred to above would exist. The system which I have illustrated, however, eliminates such reverse potential impulses. Upon cessation of conduction of the rectifier 26, the current which tends to persist in its flowing through the primary winding 21 has provided for it a low resistance path, consisting of the rectifier 27 and the conductor 28, through which said current may continue to flow. It will be seen that the direction of conduction of the rectifier 27 is such as to permit this to occur. Therefore, the current through the primary 21 continues to flow for a sufficient period of time so that the flux through the transformer 17 may gradually die down without inducing substantial voltages in said transformer. A slight reverse potential, as represented by the loop *e* in Fig. 3, does occur. However, the value of this voltage as well as the horizontal value of the voltage above zero axis is greatly exaggerated as compared with the vertical portions of curve *d*. In practice the vertical portions are of the order of several thousand volts while the horizontal portion in the loop *e* represents voltages of the order of several volts. We see, therefore, that in so far as the voltage impulses supplied to the igniting electrode 7 are concerned, they are substantially only positive impulses.

The analysis given above in connection with igniting electrode 7 applies with equal force to igniting electrode 8. The only difference is that in the case of the igniting electrode 8, the rectifier 27 picks out those impulses of the curve *c* represented in Fig. 2 as extending below the zero axis. In this case likewise, the polarities are so chosen that the substantial unidirectional voltage impulses supplied to the electrode 8 are positive.

It will be noted that in the present instance even the relatively small horizontal voltage of the curve *d* above the zero axis is positive throughout the conduction of current in its associated tube. As pointed out in my copending application, it is advantageous that whatever voltages exist on the igniting electrode shall be positive as long as any substantial conduction of current occurs in the associated tube. In this way positive ion bombardment of the insulator surrounding the conductor of the igniting electrode, which tends to make said insulating surface insensitive, is substantially prevented.

When the control contacts 29 are closed at the point where the vertical portion of curve *c* would normally occur, the igniting circuit is energized and the tubes 1 and 2 conduct current substantially as described above. If, however, the control contacts 29 are closed earlier than said point as, for example, the zero point of the line voltage wave, the voltage on each igniting electrode will rise in accordance with a sine wave variation until a sufficient voltage is impressed on said electrode to cause ignition to occur. By adjusting the ratio of transformation of each igniting transformer 17 and 18, the requisite igniting voltage can be caused to occur substantially at the normal firing point of said tube, namely the point at which the load current would normally start from a zero value. An exact adjustment of this firing point is not essential, and I prefer to have the initial firing point occur somewhat earlier. Such delayed firing beyond the zero point of the line voltage tends to make the initial flow of current coincide more closely with the normal current flow, and thus tends to eliminate transients.

The operation as described above provides an inherent protection for the igniting electrodes against application thereto of excessive voltages. During any operation of the system, the voltage applied to the igniting electrode will rise until that voltage is sufficient to cause ignition. At that instant the initiation of conduction in the associated tube causes the voltage across that tube to drop to the relatively low value of the arc drop. This effectively removes the voltage supplied to the igniting electrode. Therefore the system operates inherently so that the voltage supplied to each igniting electrode is never greater than that necessary to effect ignition. By adjusting the ratio of transformation of the igniting transformers so as to initially tend to cause the igniting electrodes to fire somewhat before the vertical portions of the curve *c*, as indicated above, at said vertical portions there is an excess igniting voltage available, if due to any reason a tube does not always fire at the minimum igniting voltage. Such variation in the required igniting voltage may be due to a number of causes; for example, variations in the level of the mercury pool with respect to the igniting electrode structure.

If one of the tubes 1 or 2 fails to become conducting upon an igniting impulse being supplied to its associated igniting electrode 1 or 2, the relay 31 operates to deenergize the igniting circuits of both tubes. This may be described in connection with the curves shown in Fig. 2. It will be seen that during normal operation of the system, the voltage which is impressed upon the operating coil 32 of the relay 31 is represented by the curve *c*. The only portions which have any substantial magnitude are the vertical portions of this curve. However, these vertical portions, as

previously described, are of such short duration that they are insufficient to cause the coil 32 to operate the relay 31. If, however, upon the occurrence of an igniting impulse at one of the igniting electrodes, the associated tube does not become conducting, the voltage across the tubes, instead of falling to the relatively low value represented by the voltage drop of the tube, continues to follow the line voltage *a*. Therefore, upon the failure of a tube to become conducting, coil 32 is supplied with a considerable voltage which persists throughout the remaining portion of the voltage wave. The relay 31 is so designed that this voltage is sufficient to cause the coil 32 to operate the relay 31. When the relay 31 is operated, the contact arm 30 opens its associated contacts, and thereafter no impulses are supplied to the igniting transformers 17 and 18. Therefore neither of the tubes 1 and 2 are permitted to fire. Under these conditions the voltage across the tubes, instead of following the curve *c*, is substantially the line voltage as represented by the curve *a*. Under these conditions the coil 32 is continuously supplied with alternating current which is sufficient to keep the relay 31 in its operated position. In order to restart the system, the contacts 29 must be opened. In ordinary resistance welding operations, the contacts 29 are periodically opened and closed in order to produce successive welding operations. Thus upon the failure of any one tube to start, the system will be deenergized throughout the remaining portion of the particular welding operation in which said failure occurs. However, during the next welding operation, the system can operate in its normal way unless a serious defect exists in either one of the two arc tubes, in which case the system cannot be restarted. This operation, therefore, accomplishes all of the protective features which are desirable in a system of this nature.

Of course it is to be understood that this invention is not limited to the particular details as described above, as many equivalents will suggest themselves to those skilled in the art. For example, some aspects of this invention may be applied to tubes having other types of igniting electrodes. Also instead of the rectifiers 26 and 27 being copper oxide rectifiers, they may be other types of rectifiers. Various other changes and additions may be made to the system as disclosed. It is accordingly desired that the appended claims be given a broad interpretation commensurate with the scope of the invention within the art.

What is claimed is:

1. In combination, an arc discharge device comprising an anode, a pool type arc cathode, and an igniting electrode adapted to initiate an arc spot on said cathode, circuit means for connecting an alternating potential between said cathode and anode, an igniting transformer having an energizing winding energized from the voltage across said arc discharge device, a rectifier in series with said winding, a circuit including a rectifier connected across said winding, and an output circuit from said transformer for supplying igniting impulses to said igniting electrode.

2. In combination, a load circuit, circuit means for connecting said load circuit to a source of alternating current, a pair of inversely-connected arc discharge devices interposed in said circuit means for controlling the flow of current to said load circuit, each of said arc discharge devices comprising an anode, a pool type arc cathode, and

- an igniting electrode adapted to initiate an arc spot on said cathode, an igniting transformer for each of said arc discharge devices, each of said transformers having an energizing winding energized from the voltage across said tube, a rectifier in series with each of said windings, and an output circuit from each of said transformers for supplying igniting impulses to one of said igniting electrodes.

3. In combination, a load circuit, circuit means for connecting said load circuit to a source of alternating current, a pair of inversely-connected arc discharge devices interposed in said circuit means for controlling the flow of current to said load circuit, each of said arc discharge devices comprising an anode, a pool type arc cathode, and an igniting electrode adapted to initiate an arc spot on said cathode, an igniting transformer for each of said arc discharge devices, each of said transformers having an energizing winding energized from the voltage across said tube, a rectifier in series with each of said windings, each of said rectifiers being connected in parallel with the winding in series with the other of said rectifiers, and an output circuit from each of said transformers for supplying igniting impulses to one of said igniting electrodes.

4. In combination, an arc discharge device comprising an anode, a pool type arc cathode, and an igniting electrode separated from said cathode by an insulating wall, circuit means for connecting an alternating potential between said cathode and anode, an igniting transformer having an energizing winding energized from the voltage across said tube, a rectifier in series with said winding, a circuit including a rectifier connected across said winding, and an output circuit from said transformer for supplying igniting impulses to said igniting electrode.

5. In combination, a load circuit, circuit means for connecting said load circuit to a source of alternating current, a pair of inversely-connected arc discharge devices interposed in said circuit means for controlling the flow of current to said load circuit, each of said arc discharge devices comprising an anode, a pool type arc cathode, and an igniting electrode separated from said cathode by an insulating wall, an igniting transformer for each of said arc discharge devices, each of said transformers having an energizing winding energized from the voltage across said tube, a rectifier in series with each of said windings, and an output circuit from each of said transformers for supplying igniting impulses to one of said igniting electrodes.

6. In combination, a load circuit, circuit means for connecting said load circuit to a source of alternating current, a pair of inversely-connected arc discharge devices interposed in said circuit means for controlling the flow of current to said load circuit, each of said arc discharge devices comprising an anode, a pool type arc cathode, and an igniting electrode separated from said cathode by an insulating wall, an igniting transformer for each of said arc discharge devices, each of said transformers having an energizing winding energized from the voltage across said tube, a rectifier in series with each of said windings, each of said rectifiers being connected in parallel with the winding in series with the other of said rectifiers, and an output circuit from each of said transformers for supplying igniting impulses to one of said igniting electrodes.

7. In combination, an arc discharge device comprising an anode, a pool type arc cathode, and an output circuit from each of said transformers for supplying igniting impulses to one of said igniting electrodes.

8. In combination, a load circuit, circuit means for connecting said load circuit to a source of alternating current, a pair of inversely-connected arc discharge devices interposed in said circuit means for controlling the flow of current to said load circuit, each of said arc discharge devices comprising an anode, a pool type arc cathode, and an igniting electrode adapted to initiate an arc spot on said cathode, an igniting transformer having an energizing winding energized from the voltage across said tube, a rectifier in series with said winding, a circuit including a rectifier connected across said winding, and an output circuit from said transformer for supplying igniting impulses to one of said igniting electrodes, and control means for controlling the connection of said winding to the energizing voltage.

9. In combination, a load circuit, circuit means for connecting said load circuit to a source of alternating current, a pair of inversely-connected arc discharge devices interposed in said circuit means for controlling the flow of current to said load circuit, each of said arc discharge devices comprising an anode, a pool type arc cathode, and an igniting electrode adapted to initiate an arc spot on said cathode, an igniting transformer for each of said arc discharge devices, each of said transformers having an energizing winding energized from the voltage across said tube, a rectifier in series with each of said windings, an output circuit from each of said transformers for supplying igniting impulses to one of said igniting electrodes, and control means for controlling the connection of said winding to the energizing voltage.

10. In combination, a load circuit, circuit means for connecting said load circuit to a source of alternating current, a pair of inversely-connected arc discharge devices interposed in said circuit means for controlling the flow of current to said load circuit, each of said arc discharge devices comprising an anode, a pool type arc cathode, and an igniting electrode adapted to initiate an arc spot on said cathode, an igniting transformer for each of said arc discharge devices, each of said transformers having an energizing winding energized from the voltage across said tube, a rectifier in series with each of said windings, each of said rectifiers being connected in parallel with the winding in series with the other of said rectifiers, and an output circuit from each of said transformers for supplying igniting impulses to one of said igniting electrodes, and control means for controlling the connection of said winding to the energizing voltage.

11. In combination, a load circuit having a power factor less than unity, circuit means for connecting said load circuit to a source of alternating current, a pair of inversely-connected arc discharge devices interposed in said circuit means

for controlling the flow of current to said load circuit, each of said arc discharge devices comprising an anode, a pool type arc cathode, and an igniting electrode separated from said cathode by an insulating wall, an igniting circuit for supplying each of said igniting electrodes with igniting impulses, and means for energizing said igniting circuits from across said arc discharge devices, whereby the voltage impulses occurring across said arc discharge devices constitute said igniting impulses.

12. In combination, a load circuit, circuit means for connecting said load circuit to a source of alternating current, a pair of inversely-connected arc discharge devices interposed in said circuit means for controlling the flow of current to said load circuit, each of said arc discharge devices comprising an anode, a pool type arc cathode, and an igniting electrode adapted to initiate an arc spot on said cathode, an igniting circuit for supplying each of said igniting electrodes with igniting impulses, means for energizing said igniting circuits from across said arc discharge devices, whereby the voltage impulses occurring across said arc discharge devices constitute said igniting impulses, and means responsive to the voltage across said arc discharge devices for deenergizing said igniting circuits when either of said arc discharge devices fails to fire and for maintaining said igniting circuits deenergized.

13. In combination, a load circuit, circuit means for connecting said load circuit to a source of alternating current, a pair of inversely-connected arc discharge devices interposed in said circuit means for controlling the flow of current to said load circuit, each of said arc discharge devices comprising an anode, a pool type arc cathode, and an igniting electrode adapted to initiate an arc spot on said cathode, an igniting circuit for supplying each of said igniting electrodes with igniting impulses, means for energizing said igniting circuits from across said arc discharge devices, whereby the voltage impulses occurring across said arc discharge devices constitute said igniting impulses, and means responsive to the occurrence of a voltage impulse of substantially longer duration than a normal igniting impulse for deenergizing said igniting circuits and for maintaining said igniting circuits deenergized.

14. In combination, a load circuit, circuit means for connecting said load circuit to a source of alternating current, a pair of inversely-connected arc discharge devices interposed in said circuit means for controlling the flow of current to said load circuit, each of said arc discharge devices comprising an anode, a pool type arc cathode, and an igniting electrode adapted to initiate an arc spot on said cathode, an igniting circuit for supplying each of said igniting electrodes with igniting impulses, means for energizing said igniting circuits from across said arc discharge devices, whereby the voltage impulses occurring across said arc discharge devices constitute said igniting impulses, and means responsive to the voltage across said arc discharge devices for deenergizing said igniting circuits when either of said arc discharge devices fails to fire and for maintaining said igniting circuits deenergized, and independent means for deenergizing said voltage-responsive means to reinitiate the operation of the system.

15. In combination, a load circuit, circuit means for connecting said load circuit to a source of alternating current, a pair of inversely-connected arc discharge devices interposed in said circuit means for controlling the flow of cur-

rent to said load circuit, each of said arc discharge devices comprising an anode, a pool type arc cathode, and an igniting electrode adapted to initiate an arc spot on said cathode, an igniting circuit for supplying each of said igniting electrodes with igniting impulses, means for energizing said igniting circuits from across said arc discharge devices, whereby the voltage impulses occurring across said arc discharge devices constitute said igniting impulses, a relay having operating means coupled across said arc discharge devices responsive to the occurrence of a voltage impulse of substantially longer duration than a normal igniting impulse, and circuit-interrupting means operated by said relay for deenergizing said igniting circuits upon the occurrence of such a long voltage impulse and for maintaining said igniting circuits deenergized.

16. In combination, a load circuit, circuit means for connecting said load circuit to a source of alternating current, a pair of inversely-connected arc discharge devices interposed in said circuit means for controlling the flow of current to said load circuit, each of said arc discharge devices comprising an anode, a pool type arc cathode, and an igniting electrode adapted to initiate an arc spot on said cathode, an igniting circuit for supplying each of said igniting electrodes with igniting impulses, means for energizing said igniting circuits from across said arc discharge devices, whereby the voltage impulses occurring across said arc discharge devices constitute said igniting impulses, and means responsive to the voltage across said arc discharge devices for deenergizing said igniting circuits when either of said arc discharge devices fails to fire and for maintaining said igniting circuits deenergized.

17. In combination, a load circuit, circuit means for connecting said load circuit to a source of alternating current, a pair of inversely-connected arc discharge devices interposed in said circuit means for controlling the flow of current to said load circuit, each of said arc discharge devices comprising an anode, a pool type arc cathode, and an igniting electrode adapted to initiate an arc spot on said cathode, an igniting circuit for supplying each of said igniting electrodes with igniting impulses, means for energizing said igniting circuits from across said arc discharge devices, whereby the voltage impulses occurring across said arc discharge devices constitute said igniting impulses, a relay having operating means coupled across said arc discharge devices responsive to the occurrence of a voltage impulse of substantially longer duration than a normal igniting impulse, circuit-interrupting means operated by said relay for deenergizing said igniting circuits upon the occurrence of such a long voltage impulse, and circuit-closing means interposed between said voltage across said arc discharge devices and said igniting circuits and said voltage-responsive means, whereby said voltage-responsive means, when operated, maintains said igniting circuits deenergized until said circuit-closing means is opened.

18. In combination, a load circuit, circuit means for connecting said load circuit to a source of alternating current, a pair of inversely-connected arc discharge devices interposed in said circuit means for controlling the flow of cur-
